UNITED STATES PATENT OFFICE.

LUDWIG SCHEIB, SR., AND LUDWIG SCHEIB, JR., OF KAISERSLAUTERN, GERMANY.

UNCOUPLING MECHANISM FOR CENTRAL-BUFFER CLAW-COUPINGS.

No. 901,560.

Specification of Letters Patent.

Patented Oct. 20, 1908.

Application filed November 14, 1907. Serial No. 402,191.

To all whom it may concern:

Be it known that we, LUDWIG SCHEIB, Sr., and LUDWIG SCHEIB, Jr., subjects of His Majesty the Emperor of Germany, residing at 5 Kaiserslautern, Germany, engineers, have invented certain new and useful Improvements in Uncoupling Mechanism for Central-Buffer Claw-Couplings; and we do hereby declare the following to be a full, clear, and exact description of the invention, such as will enable others skilled in the art to which it appertains to make and use the same.

This invention relates to uncoupling mechanism for central buffer claw couplings such 15 as are described in our application for U. S. patent filed the 27 September 1907 Serial No. 394850, said mechanism acting on the locking cap *b* therein described, to release the same from the tail of the claw hook.

20 The invention renders springs unnecessary for the uncoupling mechanism whose locking parts can be turned upon each other without injury to the movable parts and without interfering with the safety of the coupling.

25 In order that the invention may be clearly understood and readily carried into effect we will now describe the same fully as applied to the central buffer claw coupling above mentioned, having reference to the accompanying 30 drawings in which:

Figure 1 is a vertical section, and Fig. 2 a cross section of the combined arrangement; Fig. 3 is a horizontal section corresponding to Fig. 1 showing the coupling in the locked position; Fig. 4 is a similar view to Fig. 3 but showing the parts unlocked, and Figs. 5 and 35 6 are details.

Similar letters refer to like parts in all the figures, and those parts which also appear in 40 the drawings to our said earlier application bear the same reference letters as they do in those drawings.

Referring to the drawing *a* designates a hollow coupling head, and *b* a locking cap 45 pivoted on a pin *c* which may be moved back and forth in a suitable slot formed in the head *a*. The locking cap is pivotally connected to a guide rod *g* encircled by a helical spring *h*. Suitably pivoted to the coupling head *a* is a 50 claw hook *E* having a tail piece *e* which is adapted to be engaged by the locking cap *b*.

For uncoupling the parts in Figs. 1 and 3 so as to assume the position indicated in Fig. 4, it is necessary to displace the releasing pin 55 *c* towards the left. The displacement of said

pin and its retention at the rear end of its slot is effected by the improved uncoupling mechanism. To this end we provide an uncoupling lever *q* pivoted at *q'*, which is fitted with an arm provided with an inclined cam surface *r* whose lowest point is close to the releasing pin *c*. By placing the lever *q* in the position shown in dotted lines in Fig. 2, the cam surface *r* moves the releasing pin *c* backwards, together with the locking cap *b*, from the position of Fig. 2 to that of Fig. 4, thus 60 unlocking the parts. The movement of the lever *q* is limited by suitable stops and is locked when the claw hook is open.

The lever *q* is operated by means of a locking handle *s* moving in a slotted guide plate *t* and having a curved cranked end *s'* which passes through a hole in the free end of lever *q*. When the claw hook *E* of the coupling is in its locked position it is not necessary that the lever *q* should be locked since the spring *h* pushes the locking cap *b* towards the coupling claw hook and so prevents accidental disengagement. When however the coupling is unlocked, as shown in Fig. 4, it is useful to lock the lever *q* definitely in its position so as to obviate any movement by reason of the shocks experienced during shunting of the wagons. The position of the lever *q* at uncoupling is shown in dotted lines in Fig. 2 and in order to lock the same in that position the handle *s* is lifted in its slotted guide plate *t* into the round hole or enlargement *t'* thereof when it is turned axially for 90° and dropped back into the slot. By so turning the handle *s* its curved cranked end *s'* enters a second hole in the lever *q*, as shown in Fig. 6, and the latter is thereby prevented from accidental movement either in one or the other direction by reason of the weight of 70 handle *s* now rigid with the lever *q*. To prevent the handle *s* from turning back on its axis and so unlocking lever *q* accidentally, it is advisable to have that portion of the handle which moves in the slotted guide plate *t* 75 of square section.

Movements of the coupling parts during shunting or from other causes during service thus leave the uncoupling mechanism unaffected even if the distance be altered between the coupling, or rather between the pivot *q'* of lever *q*, and the guide plate *t* of its locking handle, inasmuch as the latter can readily slide longitudinally in the slot of said 80 guide plate.

What we claim and desire to secure by Letters Patent of the United States is:—

In a central buffer claw coupling, the combination with a locking cap, of a projection 5 carried thereby, a pivoted claw hook designed to be engaged by the locking cap, an uncoupling device comprising a pivoted lever provided with a cam surface adapted to engage said projection, said lever having two holes 10 in its free end, and a locking handle having a curved crank passing through one of said holes in the pivoted lever, said curved crank,

on the handle being turned axially, passing through the other hole in the lever and thus locking the same against accidental movement, substantially as set forth. 15

In testimony whereof we have hereunto set our hands in the presence of two witnesses.

LUDWIG SCHEIB, SENIOR.
LUDWIG SCHEIB, JUNIOR.
